LIQUID CLARIFICATION APPARATUS

Arthur C. Lind and William J. Katz, Milwaukee, Wis., assignors to Chain Belt Company, Milwaukee, Wis., a corporation of Wisconsin

Application March 6, 1956, Serial No. 569,715

1 Claim. (Cl. 210—221)

This invention relates to the clarification of liquids which are carrying suspended impurities, such as sewage, industrial wastes and the like, and has for its principal object the provision of an improved apparatus for continuously separating the impurities from the carrying liquid with a high degree of efficiency, whereby the liquid may be discharged from the apparatus in a substantially pure state while the impurities may be either sent to waste or recovered for further use if desired.

The impurities carried by the liquids with which the invention is primarily concerned usually have a specific gravity approximately the same or only slightly higher than that of the carrying liquid, and although at least a substantial portion of them usually can be separated from the liquid by sedimentation, such procedure is so relatively slow that where great quantities of liquid must be handled, large and expensive installations are necessary. On the other hand, it has been previously recognized that in view of the near-equality of the specific gravities of the liquid and the impurities, separation of the two may also be accomplished by flotation methods having at least some analogy to those widely employed in the separation of ores, i.e., by subjecting the impure liquid to the action of air or other gas bubbles which attach themselves to the suspended impurities and float them to the liquid surface.

It is also known that in the clarification of liquids in this manner the best results are obtained through the use of gas bubbles of extremely small size and several methods and means for providing minute bubbles have been proposed, among them the entrainment or dissolution of the gas in water, which mixture is then introduced into a body of the impure liquid contained in a clarification tank of appropriate size. One of the principal difficulties encountered in a system of this character has been incomplete mixing of the impure liquid with the gas-liquid solution resulting in low hydraulic efficiency and consequent large size in the clarification apparatus. Accordingly, it is a principal object of the present invention to provide at least two hydraulic zones, in the first of which control may be exercised over the mixing of impure liquid with gas-liquid solution and in the second of which flotation of suspended particles may take place. It is a corollary object to the foregoing to provide a proper mechanical and hydrostatic combination of the zones whereby the mixed incoming flow is caused to disperse throughout the flotation zone and utilize the full volume thereof, with consequent improved efficiency and material reduction in the size and cost of the apparatus required to handle any given quantity of liquid. Other objects will appear as the description proceeds.

Two forms of apparatus constructed in accordance with the invention have been illustrated by way of example in the accompanying drawings constituting a part of this specification, in which:

Figure 1 is a plan view of a typical form of the apparatus, with the skimming mechanism for removing the

2

floated impurities from the liquid surface omitted for the sake of clearness;

Fig. 2 is a side elevational view of the apparatus shown in Fig. 1, with the skimming mechanism in place;

Fig. 3 is a central longitudinal sectional view of the apparatus shown in Figs. 1 and 2, looking in a direction opposite to that of Fig. 2;

Fig. 4 is a transverse sectional view taken on the plane indicated by the line 4—4 in Fig. 3, looking in the direction of the arrows;

Fig. 5 is a view similar to Fig. 4 but taken on the plane indicated by the line 5—5 in Fig. 3, looking in the direction of the arrows;

Fig. 6 is a fragmentary longitudinal sectional view similar to Fig. 3 of a slightly modified form of the apparatus; and

Fig. 7 is a fragmentary transverse sectional view on the planes indicated by the line 7—7 in Fig. 6, looking in the direction of the arrows.

Referring more particularly to Figs. 1—5 inclusive, 10 indicates an open-topped clarification tank, here shown as constructed of metal and comprising the side walls 11 and 12, end walls 13 and 14, and a bottom wall or floor 15. A pipe or conduit 16 conducts the impure liquid to the said tank, into which it is introduced through the branches 17 extending through the end wall 13 and discharging behind a baffle 18. A pipe 19 extends through the opposite end wall 14 for discharging the clarified liquid from the tank.

At the head or influent end of the tank there is provided a transverse partition 20 extending from the floor 15 to somewhat above the liquid level 21 and dividing the tank into a comparatively small influent or mixing chamber 22 and a considerably larger separation or flotation chamber 23. As best shown in Fig. 4 the partition wall 20 is provided with a transverse series of relatively narrow vertical slots or perforations 24 extending substantially from top to bottom of the wall and affording restricted communication between the chambers 22 and 23 throughout substantially their entire cross sectional area. The partition 20 is preferably retained by guide ways (not shown) fixed to the side walls 11 and 12 so that the partition may be removed for periodic cleaning.

At the discharge or effluent end of the tank it is provided with a second transverse partition 25, the upper portion of which is equipped with a vertically adjustable weir 26 whereby the liquid level in the chamber 23 may be controlled. Since, as will be clear from Figs. 2 and 3, the effluent pipe 19 is located at the upper portion of the tank, the space between the partition 25 and the end wall 14 constitutes a well 27 in which a quantity of clarified liquid will always be present, even though the flow of raw liquid through the influent conduit 16 may be reduced or temporarily suspended. Thus, a supply of clarified liquid is always available for aeration, as will appear more fully below.

Just ahead of the well-forming partition 25 the tank is provided with a scum receptacle 28, extending across the upper portion thereof, and which receptacle has a discharge pipe 29 leading from its lower portion. A transverse baffle plate 30 depends from the scum trough 28 as shown in Figs. 3 and 5, and in conjunction with said trough prevents floated impurities from reaching the weir 26 thereby insuring that only clarified liquid will exit from the chamber 23 to the well 27.

As best shown in Figs. 1 and 2, the apparatus for supplying gas—usually air—to the impure liquid comprises a motor-driven pump 31 mounted exteriorly of the tank 10 and from the intake side of which a suction pipe 32 extends into the wet-well 27. The discharge side of said pump is connected by a pipe 33 to the lower portion of a closed tank 34 and said pipe 33 is provided with

a connection 35 through which air or other gas may be supplied to the liquid flowing through such pipe for dissolution therein. The tank 34 has a vertical baffle 36 extending across it and upwardly from its bottom to adjacent its top, and the pipe 33 discharges into said tank to one side of such baffle while a pipe 37 leads from the tank at the other side of the baffle. The tank 34 is of such capacity in relation to the flow of liquid provided by the pump 31 that the liquid will be held in said tank under pressure for a time sufficient—usually from one to two minutes—for it to become substantially saturated with the gas introduced through the connection 35. The baffle 36 insures detention of the liquid for the necessary period by preventing short-circuiting thereof between the pipes 33 and 37.

The pipe 37 leads to an automatic pressure-regulating valve 38 located adjacent the exterior of the influent chamber 22, and a pipe 39 leads from such valve to a distribution header 40 which is disposed in and extends across the lower portion of said influent chamber, adjacent the end wall 13 of the tank 10. The said header may comprise a length of pipe provided with a longitudinal series of perforations 41 through which the pressurized gas-saturated liquid from the pipe 39 may be discharged into the raw impure liquid in said chamber 22 in the form of upwardly and rearwardly directed jets. Inasmuch as the liquid in the chamber 22 is under only normal atmospheric pressure, the discharge of the super-atmospherically pressurized gas-saturated liquid thereinto has the effect of liberating the gas in the form of myriads of minute bubbles which, in the case of many impure liquids, are thoroughly dispersed through the body of such liquid in said chamber by the agitating action of the jets alone. In the case of some impure liquids however, it may be desirable to assist this dispersal by means of mechanical agitators such as the rotatable paddles 42 located in the receiving chamber.

The liquid in chamber 22 is continuously transferred therefrom to the chamber 23 through the perforated partition 20, which protects the liquid in the latter chamber against substantially all of the agitation taking place in the former chamber and provides a relatively quiescent body of liquid in which the minute gas bubbles may the better attach themselves to the suspended impurities and carry them to the surface of the liquid. The combined area of the series of slots 24 in the partition 20 is much less than the cross sectional area of the tank 10 and the said partition thus creates a hydraulic head in the chamber 22 which is sufficient to produce substantially complete diffusion of the liquid and gas bubbles passing through the slots 24 to all parts of the chamber 23, thereby avoiding short-circuiting and leaving no dead spots in the body of liquid in such chamber. As a result the efficiency of the present apparatus is appreciably higher than that of the previously proposed installations of similar nature and for any given volume of impure liquid to be handled, it may be correspondingly smaller.

A valve-controlled pipe 43, communicating with the chamber 23 adjacent the effluent end of tank 10, may be provided for draining the tank when necessary.

As shown in Figs. 2-5, mechanical skimming mechanism may be provided for positively removing the floated impurities from the tank. This mechanism comprises a framework 45 surmounting the tank 10 and including superposed pairs of transversely spaced guides or rails 46 and 47 which respectively support the upper and lower runs of a pair of endless chains 48 that are trained about head sprockets 49 and tail sprockets 50 which are suitably journaled in said framework. The head sprockets 49 are driven by an appropriate source of power 51 through a chain-and-sprocket drive 52. The chains 48 pendently carry between them a plurality of transversely extending skimming blades 53 which, during their travel from left to right as viewed in Fig. 3, break the surface

21 of the liquid in both of the chambers 22 and 23 of the tank 10 and positively move any material floating on said surface to and into the receptacle 28, from which it is discharged through the pipe 29. An inclined apron 54 may be provided ahead of the upper portion of the partition 20 to assist the blades 53 in transfer of the floatage in chamber 22 over said partition.

In the form of the apparatus illustrated in Figs. 6 and 7 the mechanical agitator is omitted from the chamber 10 22 of the tank, and the diffusion partition 55, instead of being slotted as in Fig. 4, is provided with a plurality of holes 56 through which the liquid and gas bubbles pass from the chamber 22 to the chamber 23. A combined sludge and skimming conveyor 57, of a flight type well known in sewage treatment and other liquid purification fields, is shown in lieu of the skimming mechanism above described and illustrated in Figs. 2-5. Such impurity-removing mechanism may be desirable in certain cases where some of the impurities will unavoidably settle to 20 the floor 15 of the tank even though most of them can be floated to the liquid surface.

In some applications the rates of flow and characteristics of the liquid being treated may indicate the desirability of a non-mechanical mixer, one type of which is 25 illustrated in Fig. 6. As shown, the form of mixer comprises a baffle 18' which extends transversely from the side walls of the tank and upwardly above the liquid level in the tank 10. At its lower edge the baffle 18' terminates slightly above the distribution header 40. A 30 horizontal baffle 58 is shown fixed to the wall 13 at an elevation above the header 40, it being understood that this baffle likewise extends transversely between the side-walls of the tank. The forward edge of the horizontal baffle 58, in conjunction with the lower edge of the vertical baffle 18' creates a slit-like opening 59 through 35 which all of the influent liquid must pass. The perforations 41 in header 40 may be oriented to direct jets of pressurized gas-saturated liquid across this opening 59 so that thorough mixing of the two streams occurs.

40 Fig. 6 also illustrates a revolving scum pipe 60 of a type well known in the art for removing scum in the mixing zone 22, it being understood that such a device may not be required in all instances. The details of scum pipe 60 are completely described in Patent No. 2,337,859 to F. G. Stuller. It is operated by tilting its open top until one edge of the opening is slightly submerged, in which position water will flow into the pipe carrying floating scum therewith.

What is claimed is:

50 Apparatus for the continuous separation of impurities from liquids in which they are suspended, comprising an open tank for containing a body of the liquid under normal atmospheric pressure; a perforated partition in said tank dividing it into a single localized influent chamber and a single substantially larger separation chamber, the apertures in said partition providing restricted communication between such chambers whereby a hydraulic head may be maintained in the influent chamber, and said apertures being so spatially arranged in the partition as to insure diffusion of fluid passing therethrough to all portions of the separation chamber while at the same time preventing undue agitation of the body of liquid in such chamber, thus maintaining it in a relatively quiescent state most conducive to flotation of the impurities carried thereby; means for supplying the impure liquid to said influent chamber; means for continuously discharging directly into the impure liquid in said influent chamber a super-atmospherically pressurized liquid containing a dissolved gas which gas is liberated in the form of minute bubbles by the pressure drop within the chamber, which bubbles upon passage through the perforated partition under the action of said hydraulic head are diffused to all parts of said separation chamber, said discharging means comprising a perforated header extending transversely of the localized influent chamber in

the lower portion thereof; baffle means in the influent chamber arranged to direct the entire impure liquid influent to the region of said pressurized-liquid discharging means, said baffle means comprising a vertical baffle element arranged to direct the incoming impure liquid downwardly to the region of said header, and a horizontal baffle element adjacent the lower portion of said vertical element, the lower edge of the vertical element and the rearward edge of the horizontal element being spaced to provide between them a narrow horizontally extending discharge port adjacent the header through which said impure liquid influent is discharged across the pressurized-liquid discharge whereby to effect a thorough blending of the two liquids; means for discharging clarified liquid from the separation chamber; and means for removing the separated impurities from the chambers.
